UNITED STATES PATENT OFFICE.

CHARLES A. STURTEVANT, OF PLAINFIELD, NEW JERSEY, ASSIGNOR TO E. C. FULLER COMPANY, OF NEW YORK, N. Y., A CORPORATION OF NEW YORK.

PACKING MECHANISM FOR FOLDING-MACHINES.

No. 879,841.

Specification of Letters Patent.

Patented Feb. 18, 1908.

Original application filed January 23, 1905, Serial No. 242,273. Divided and this application filed May 22, 1906. Serial No. 318,175.

To all whom it may concern:

Be it known that I, CHARLES A. STURTEVANT, a citizen of the United States, residing at Plainfield, in the county of Union and State of New Jersey, have invented a new and useful Improvement in Packing Mechanism for Folding-Machines, of which the following is a specification.

This invention relates more particularly to a folding machine capable of folding a sheet of paper or the like into a signature having one or more parallel or right angle folds, but some of the features are also applicable to other types of folding machines.

15 The objects of this invention are to improve the means whereby one of the stacker boxes may be adjusted to suit different sizes of signatures independent of the other stackers and also to improve and to simplify 20 the means for operating a plurality of packers.

This is a subdivision of an application on which Letters Patent of the United States were granted July 3, 1906, and numbered 824,754.

25 In the accompanying drawings consisting of 5 sheets: Figure 1 is a top plan view of a sheet folding machine embodying my improvements. Fig. 2 is a detached horizontal sectional view of the mechanism for operating a plurality of packers. Fig. 3 is a vertical longitudinal section, on an enlarged scale, taken in line 3—3, Fig. 1. Figs. 4 and 5 are vertical transverse sections taken on the correspondingly numbered lines in Fig. 1. 35 Fig. 6 is a fragmentary vertical longitudinal section of one of the folding and stacking devices taken in line 6—6, Fig. 4. Fig. 7 is a fragmentary vertical section, on an enlarged scale, in line 7—7, Fig. 4, showing the 40 box elevating mechanism of the last mentioned stacking device. Fig. 8 is a horizontal section in line 8—8, Fig. 7.

Similar letters of reference indicate corresponding parts throughout the several views.

45 In its general organization, this folding machine consists of a main frame A, a feed board or table a arranged at the front end of the frame and adapted to support the pile of sheets to be folded into signatures, a 50 first pair of folding rollers b, b¹ arranged in the upper part of the frame in rear of the table and adapted to produce the first fold in the sheet, a second pair of folding rollers c, c¹ arranged at right angles to the first pair 55 and receiving the sheet therefrom, a third

pair of folding rollers d, d¹ arranged parallel to the first pair and receiving the sheet from the second pair, a fourth pair of book folding rollers e, e¹ arranged parallel to the second pair and receiving the sheet from the third pair of book rollers, a third pair of periodical folding rollers f, f¹ arranged parallel to the first pair and receiving the sheets from the second pair, a fourth pair of periodical folding rollers g, g¹ arranged parallel to the third pair of periodical rollers f, f¹ and receiving the sheets therefrom, and a fourth pair of periodical folding rollers h, h¹ arranged parallel to the second pair. These several pairs of rollers are all arranged horizontally, the first pair being arranged lengthwise in the upper part of the frame, the second pair in front of the first, the third pair of book rollers d, d¹ and the third pair of periodical rollers f, f¹ being arranged parallel to the first and on opposite sides of the second pair, the fourth periodical rollers g, g¹ being in rear of the third pair f, f¹ and the fourth periodical rollers h, h¹ being to the left of the third periodical rollers f, f¹. Each pair of 70 these rollers may be driven in any suitable manner from the horizontal driving shaft I which is journaled transversely in the frame. 75

The sheet propelling mechanism comprises a set of tapes B which carry the sheets from the feed board to the first rollers, a set of tapes C which carry the sheets from the first to the second rollers, a single set of tapes D which carry the sheets from the second rollers either to the fourth periodical rollers h, h¹ or to the third book rollers d, d¹ or the third periodical rollers f, f¹, a set of tapes E which carry the sheets from the third book rollers d, d¹ to the fourth book rollers e, e¹, and a set of tapes F which carry the sheets from the third periodical rollers f, f¹ to the fourth periodical rollers g, g¹. 80 85 90 95

The first tapes B pass at their receiving and delivery ends around receiving and delivery rollers b², b³, the second tapes C pass at their receiving and delivery ends around the roller b of the first pair and around tightener rollers b⁴, the third tapes D pass transversely underneath the second rollers and lengthwise of both pairs of third rollers which are parallel to the first and at one end around the roller h of the fourth pair parallel to the second, while their opposite ends pass around guide rollers d², on the main frame, the book tapes E pass at their front and rear 100 105 110

ends around receiving and delivery rollers e^2 , e^3 , and the periodical tapes F pass at one end around the roller g and at the opposite end around a roller f^2 , while the intermediate portions of the same pass over the roller f^1 and underneath the roller f, as shown in Figs. 3, 4 and 5.

K—K⁶ are the several folding blades which coöperate with the folding rollers of the first 10 pair, second pair, third book pair, fourth book pair, third periodical pair parallel to the first, fourth periodical pair parallel to the second and the fourth periodical pair parallel to the first, respectively, each blade being 15 arranged above its respective pair of rollers and movable vertically toward and from the space between the same. Each of these folding blades is mounted on the free ends of one or more rock arms k^1 which are secured to a 20 horizontal rock shaft k^2 which is journaled in bearings on the frame.

When it is desired to produce a periodical signature having one longitudinal fold and two successive parallel folds, the sheet is 25 passed through the first rollers, the second rollers and the fourth rollers parallel to the second. Upon passing the sheet successively through the first rollers, the second rollers, the third periodical rollers parallel to 30 the first, and the fourth periodical rollers parallel to the third periodical rollers, the sheet will be folded accordingly suitable for periodicals. If it is desired to produce a book signature having one transverse fold 35 and two longitudinal folds, the sheet is passed successively through the first rollers, the second rollers and the third book rollers d , d^1 . Additional folds parallel to the first and second may be produced in the book signature 40 by passing the sheet as it issues from the second rollers through the third and fourth book rollers d , d^1 , e , e^1 .

When folding a book signature the tapes over the two-third pairs of rollers d , d^1 , f , f^1 45 are moved in the direction of the arrow, Fig. 3, whereby the sheet upon issuing from the second rollers will be carried over the third book rollers. If however the sheet is to be folded into the form of a periodical signature, 50 the direction of movement of the tapes is reversed so as to carry the sheet issuing from the second rollers either to the third periodical rollers which are parallel to the first or to the fourth periodical rollers which are parallel to the second. When the sheet is carried 55 from the second rollers over the third book rollers, the forward movement of the same in that direction is arrested by a gage d^3 . A similar gage f^3 , shown in dotted lines in Fig. 60 3, is provided when the sheet is to be carried from the second rollers to the third periodical rollers which are parallel to the first. If however the sheet is to be carried directly from the second rollers to the fourth periodical rollers h , h^1 , then the gage f^3 is removed 65

permitting the sheet to move forward to the gage h^2 in position to be folded by the blade K⁵ and rollers h , h^1 .

For the purpose of enabling the machine to be set so as to direct the sheet from the second rollers either toward the book rollers or the periodical rollers which are arranged on opposite sides thereof, a switch mechanism is provided which consists essentially of a plurality of switch or deflector rollers N 70 which are arranged between the lower opposing parts of the coöperating second rollers. These deflector rollers are mounted upon a rocking support which permits the same to be swung into engagement with the lower 75 side of either of the second rollers c , c^1 and which consists of upright rock arms n carrying the deflector or switch rollers, and the rock shaft n^1 to which the lower ends of the rock arms are secured. Upon rocking the 80 shaft in the direction for engaging the deflector rollers N with the folding roller c , as shown in Fig. 3, the sheet issuing from the undersides of the second rollers will be directed by the deflecting rollers underneath 85 the roller c of said pair causing the same to be carried to the third book rollers by the tapes D which are moving in that direction. Upon turning the rock shaft n^1 so as to carry 90 the deflector rollers against the folding roller c^1 the sheet passing downwardly between the two rollers c , c^1 will be directed around the underside of the roller c^1 toward the periodical folding rollers in which direction the same will be carried by employing the proper 95 gearing for causing the tapes D to move in that direction.

For the purpose of causing the sheet upon issuing from the underside of the third book rollers to be discharged either into a stacker 100 box below the same or to the fourth book folding rollers e , e^1 for producing another fold in the same, the rollers e^2 which carry the receiving ends of the back tapes E are 105 adjustably supported so as to be bodily movable into and out of the path of the sheets as they issue from the third book folding rollers d , d^1 . When it is desired to discharge the completed signature directly downward from the third book rollers, the 110 tape rollers e^2 are withdrawn inwardly or out of the path of the signature as the same issues from the underside of the third book rollers, as represented in Fig. 4. When it is desired to direct the sheets from the third 115 book rollers to the fourth book rollers, the tape rollers e^2 are moved outwardly and upwardly into the space between the lower parts of the third book rollers, thereby causing the same to intercept the sheet issuing 120 from these rollers and direct the same to the fourth book rollers.

The improved means for stacking or piling the folded signatures as they issue downwardly from the several final folding rollers, 125

are constructed as follows: U, U¹, U², U³ represent the receiving or packing boxes of the several stacking devices which are arranged respectively below the third book rollers d, d¹, the fourth book rollers e, e¹, the fourth periodical rollers h, h¹ which are parallel to the second, and the fourth periodical rollers g, g¹ which are parallel to the first. These boxes are arranged to open outwardly from four sides of the machine. u, u¹ u², u³ represent the packers which are movable horizontally lengthwise in these boxes and operate to push the signatures forwardly in the same after being delivered by the respective folding rollers into the boxes. Each of the packers u, u², u³ is guided by means of a pair of sliding rods u⁴ to which the packer is secured and which are guided in the slotted central part of the respective box by guides u⁵, as shown in Figs. 3, 4 and 5. The packer u¹ is secured to a single horizontal slide rod u⁶ which moves lengthwise of the box U¹ and supported in guides u⁷ secured to the lower side thereof, as shown in Figs. 4 and 6. V represents an upright packer or rock shaft from which all of the packers of the several stacking devices are simultaneously operated. This shaft is journaled in the adjacent part of the main frame and is actuated by means of a cam v arranged on the cam shaft I¹, a rock arm v¹ connected with the packer shaft and a slide v² connected at one end by a link v³ with the rock arm v¹ and provided at its opposite end with a roller which engages with a groove in the cam v. The packer u is operated from the packer shaft by a rod or link w connected at one end with a rock arm w¹ on the packer shaft while its opposite end is pivotally connected with the guide rods of said packer u, as shown in Figs. 2, 3 and 5. A similar rod or link w² connects the guide rods of the packer u³ with a rock arm w³ on the packer shaft for operating this packer, as shown in Figs. 1, 3 and 5. Motion is transmitted from the packer shaft to the packer u² by a rock lever w⁴ pivoted on the adjacent part of the frame, a link or rod w⁵ connecting one arm of this lever with the guide rods of the packer u² and a link or rod w⁶ connecting the other arm of said lever with a rock arm w⁷ on the packer shaft. The packer u¹ is operated from the packer shaft by an upright guiding or adjusting rod W which is secured at its upper end to a rock arm w⁷ and at its lower end to a similar rock arm w⁸ secured to the lower part of the packer shaft, and a link or rod w⁹ mounted loosely at one end on the adjusting rod W, and pivotally connected at its opposite end to the slide rod u⁶. Upon oscillating the packer shaft, the several packers are simultaneously moved forward and backward in their respective boxes, causing the blanks to be stacked in whichever box the same are being delivered. The parts of the

machine are so timed that while each packer is retracted into its rearmost position the signatures are fed by the respective folding rollers into the box in front of the packer after which the packer advances and pushes the signature forwardly against the stack in the box. This manner of constructing and operating the packing mechanism of a plurality of stacking devices is very simple in construction and materially reduces the cost of the machine. 70

The side walls u⁸ of each of the boxes U, U², U³ are capable of transverse adjustment on the bottoms u⁹ thereof for adapting the same to different sizes of signatures, this being effected by means of bolts u¹⁰ passing through angle pieces u¹¹ on the outer sides of the box walls and through slots u¹² in the bottom of these boxes, as shown for instance in Figs. 1, 3 and 5. These boxes are however not adjustable vertically inasmuch as the signatures which are delivered into the same do not vary sufficiently in size to make this necessary. The box U¹ which receives the signature from the fourth book rollers e, e¹ has its sides inclined and it is made vertically adjustable in order to permit of adapting the same for reliably receiving signatures which vary considerably in size. The mechanism for adjusting the height of this box is best shown in Figs. 3-8 and is constructed as follows: X represents a vertical shank or post preferably of tubular form which supports the stacking box U¹ at its upper end. On its outer side this shank carries a vertical gear rack x¹ which meshes with a gear pinion x². x³ is a bracket secured to the main frame and provided with a vertical socket x⁴ in which the shank is guided, and a horizontal bearing x⁵ at one side in which the gear pinion x² is journaled. Upon turning the pinion in one direction or the other, the gear rack together with the shank and box connected therewith are raised or lowered as may be necessary for adapting the same to the size of signatures which are being delivered into the box. The gear pinion is turned for this purpose by means of a pin or handle x⁶ which is inserted in one or another of a plurality of annular openings x⁷ formed in the outer end of the pinion. For the purpose of permitting the stacking box U¹ to be held in position after adjustment the bracket x³ is split transversely from its guide socket through its bearing, as shown at x⁸ and the split parts of the bracket are pressed or clamped against opposite sides of the shank for holding the same in place. The means for this purpose shown in the drawings consist in providing the gear pinion with an inwardly facing shoulder x⁹ which engages one of the split parts of the bracket, a tie rod or clamping bolt x¹⁰ arranged centrally in the gear pinion and secured at one end to the other section of the split bracket, and a clamping nut x¹¹ arranged on the opposite 130

end of the clamping bolt and bearing against the outer end of the gear pinion. Upon tightening this nut the gear pinion is pressed against the adjacent split part of the bracket 5 and the two parts of the latter are drawn against opposite sides of the box supporting shank X, thereby holding all of these parts firmly against movement after being adjusted.

As the stacking box is raised and lowered 10 for adapting the same to different sizes of signatures, the link w⁹ of its packer slides up or down on the rod W which is connected with the packer shaft. The operative connection between the packer shaft and the 15 packer of the box U¹ is therefore not disturbed upon raising and lowering the packer box, thereby avoiding the necessity for any separate adjustment for this purpose.

I claim as my invention:

20 1. A folding machine comprising an upright packer shaft, a plurality of stacking boxes arranged around said shaft and extending horizontally in different directions therefrom, packers movable lengthwise in said 25 boxes, operating connections between said packers and said shaft, one of said connections together with the corresponding packer and box being vertically adjustable relatively to said shaft without disturbing the other 30 connections, packers and boxes, substantially as set forth.

2. A folding machine comprising an upright packer shaft, a plurality of stacking boxes arranged around said shaft and extending 35 horizontally in different directions therefrom, packers movable lengthwise in said boxes, and operating connections between said packers and said shaft consisting of a plurality of rock arms arranged on said shaft, 40 and rods connecting said arms with said packers, substantially as set forth.

3. A folding machine comprising a plurality of stacking boxes, packers reciprocating horizontally in said boxes, slides supporting said packers, an upright rock shaft 45 provided with a plurality of rock arms, rods

connecting some of said rock arms directly with the slides of some of the packers and a rock lever having one of its arms connected by a rod with one of the rock arms of said shaft while its other arm is connected by a rod with the slide of one of said packers, substantially as set forth. 50

4. A folding machine comprising a vertically adjustable stacker box, a packer reciprocating in said box, a slide guided on the box and carrying said packer, an upright rock shaft, an upright adjusting bar connected by rock arms with said shaft, and a link pivoted directly at one end on the slide of said packer 60 and capable of sliding at its opposite end on said adjusting bar, substantially as set forth. 65

5. A folding machine comprising a stacker box, an upright shank carrying said box, an adjusting pinion meshing with a gear rack on 70 the shank, a bracket having a socket in which the shank is guided, a bearing in which the pinion is journaled and a split through said socket and bearing, and a clamping device for drawing the split parts of the bracket 75 together, substantially as set forth.

6. A folding machine comprising a stacker box, a bracket having a socket, a bearing and a split through said socket and bearing, a shank carrying said box and guided in said 80 socket, a gear pinion journaled in said bearing and having a shoulder which bears against one of the split parts of said bracket, a gear rack arranged on said shank and meshing with said pinion, a clamping bolt arranged 85 centrally in said pinion and secured at one end to the other split part of said bracket, and a nut arranged on the opposite end of said bolt and bearing against the outer end of said pinion, substantially as set forth. 85

Witness my hand this 18th day of May, 1906.
